UNITED STATES PATENT OFFICE.

HERMAN IHLENBURG, OF PHILADELPHIA, PENNSYLVANIA, ASSIGNOR TO MACKELLAR, SMITHS & JORDAN, OF SAME PLACE.

DESIGN FOR A FONT OF PRINTING-TYPE.

SPECIFICATION forming part of Design No. 13,859, dated April 17, 1883.

Application filed March 12, 1883. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of a letter of the class known as "script," the letters being composed of a series of light and heavy lines, as shown, many of them having at bottom the flourishes or curved terminations followed by the heavy dot, while in others the cross portions upon the right are ornamented by a curved line terminating in a heavy dot. Of the first class may be cited the B, D, E, F, I, L, W, Y, and Q; of the second class the C, E, F, G, S, and T. In the A, H, and N the flourish is found at the base of the letter upon the left and extended below the line. In the A and G the central portion of the letter is or.

namented by the line having at one extremity a dot above and at the other extremity a dot 25 below. The tail of the Q is formed by a vertical line extending downward, followed at its base upon the right by a short curved line. In the lower-case the b, d, h, k, and l have the up-and-down portion inclined upon the upper 30 left hand. The c, f, g, and t have the short line terminating in the dot. The upper portions of the u, v, w, and y have the short horizontal line and dot termination, and the Q is crossed by the central curved line.

The character of the design is preserved in the numerals, notably in the 2, 3, 5, 7, 8, and 9.

Having now described my invention, I claim as new—

The design for a font of printing-type, as shown and described.
